BY Victor J. Evans

ATTORNEY

UNITED STATES PATENT OFFICE

HERBERT A. TROTMAN, OF NORTH SAN DIEGO, CALIFORNIA

PLUG FOR SINKS

Application filed December 20, 1929. Serial No. 415,494.

This invention relates to improvements in devices for arresting the flow of water in sinks through the drains leading therefrom, and has as its general object to provide a device which may be employed by merely disposing the same over the perforated drain plate in the sink, where it will be held in place by the water flowing into the sink, so that the sink, in connection with which the device is employed, may be used for washing dishes, pans, and clothing, this being more convenient than the use of a dish or other type of pan, inasmuch as the ordinary sink is supplied with water from both hot and cold faucets and therefore water at any desired temperature may be obtained.

Another object of the invention is to provide a device for the purpose stated which will be extremely simple in construction and which will be so constructed as to preclude any displacement thereof in the event any of the articles, to be washed, come in contact therewith, the invention contemplating a device of this class which will primarily be held against displacement, in a very firm manner, by the weight of the volume of water in the sink, together with an auxiliary retaining means which will coact with the perforated drain plate of the sink to likewise resist any displacement of the device.

This invention also consists in certain other features of construction and in the combination and arrangement of the several parts, to be hereinafter fully described, illustrated in the accompanying drawing, and specifically pointed out in the appended claims.

In describing my invention in detail, reference will be had to the accompanying drawing wherein like characters denote like or corresponding parts throughout the several views, and in which:—

Figure 1 is a diametric sectional view through the device embodying the invention arranged within a sink and upon the perforated drain plate thereof.

Figure 2 is a top plan view of the device removed from the sink.

Figure 3 is a bottom plan view of the device removed.

50 The device embodying the invention com-

prises an annular stopper disk 1 which is of soft rubber, and in the central opening 2 of this disk there is fitted a cap member, which is indicated in general by the numeral 3, and which may be stamped from sheet metal and comprises an annular wall 4, an annular outstanding rim 5, and a bottom 6.

The wall 4 of the cap member is of a diameter to fit snugly into and substantial filling the opening 2 in the stopper disk 1, with the under side of the bottom 6 of the cap member occupying the same plane as the under side of the said stopper disk, and with the rim 5 resting upon the upper side of said disk. The stopper disk 1 is of a diameter equal to or slightly greater than that of the drain closure or plate which is indicated by the numeral 7, and which is formed with the usual perforations indicated by the numeral 8, and inasmuch the bottom of the cap member is in the same plane as the underside of the disk 1, the weight of the water introduced into the sink from the faucets, will securely hold the device in place when arranged in the manner shown in Figure 1.

In order that the device may be conveniently handled and in order to provide an auxiliary means for holding the device against displacement when arranged upon the drain plate 7, a bail 9, made of wire, is provided and this bail includes a finger grip portion 10 which is straight and of a length less than the diameter of the wall 4 of the cap member, the wire being bent back upon itself as indicated by the numeral 11 so as to provide inturned portions 12 which rest upon the upper side of the bottom 6 of the cap member. These portions 12 terminate in downwardly extending right angular portions 11 which have their extremities turned in opposite directions as indicated by the numeral 13, so that, when the device is arranged in the manner shown in Figure 1, the portions 11 may be engaged through two diametrically oppositely located ones of the openings 8 in the drain plate 7 and, by a slight rotation of the device, the right angular terminal portions 12 may be caused to engage beneath the said plate 7 thus positively preventing upward displacement of the 103

device until it is intentionally rotated the required distance to permit of passage of the members 11 and their extremities 13 through the openings and lifting of the device by 5 prying up one side of the disk 1 or by an upward pull upon the finger piece 10 of the bail 9.

What I claim is:—

1. A device of the class described comprising an annular disk of rubber, a head to which the disk is fitted, the head having a portion extending downwardly into the opening in the annular disk, and substantially flush at its bottom with the under side of the disk 15 and a finger piece connected with said head, the head being open at its upper side and provided in its bottom with diametrically oppositely located openings, and the said finger piece having depending end portions engaging through said openings, and having right angularly turned terminals extending in opposite directions with respect to the circumference of the disk, whereby, when the device is disposed upon a perforated drain plate 20 and lowered to engage the terminals through diametrically opposite openings in the drain plate, and the device as a whole is rotated, the said terminal portions may engage beneath the drain plate.

30 2. In a plug for application to the upper side of the perforated closure plate of a sink drain, an annular plug body of rubber, a cap member comprising a hollow cylindrical body open at its upper side and fitted in the 35 opening of the annular plug body, and a bail seated in the said cap member and having spaced integral portions extending downwardly through the bottom of the cap member at opposite sides of the center thereof and engageable through correspondingly 40 located ones of the openings in the closure plate, the lower terminals of the said portions being turned in opposite directions with respect to the circumference of the disk 45 to engage beneath the closure plate adjacent the openings through which the portions extend when the plug is bodily rotated after insertion of the terminals through the openings.

50 3. In a plug for application to the upper side of the perforated closure plate of a sink drain, an annular plug body of rubber, a cap member comprising a hollow cylindrical body opened at its upper side and fitting frictionally within the opening in the said plug body, a flange surrounding the open upper side of the cap and engaging the upper side of the plug body adjacent the said opening therein, and a bail of wire comprising a 55 finger piece portion and end portions bend downwardly and inwardly to extend beneath the finger piece portion, and thence downwardly through the openings in the bottom of the cap member below said bottom, whereby to project downwardly through openings 60 65

in the said closure plate, the lower terminals of the said downwardly extending portions being presented in relatively opposite directions whereby to engage beneath the closure plate upon slight rotation of the plug, as a 70 whole.

In testimony whereof I affix my signature.

HERBERT A. TROTMAN.
